Primary Examiner — Marie D. Fast Horse*(74) Attorney, Agent, or Firm* — Muetting, Raasch & Gebhardt, P.A.(57) **CLAIM**

The ornamental design for a storage device, as shown and described.

DESCRIPTION

FIG. 1 is a front right perspective view of a storage device in accordance with the claimed design;

FIG. 2 is a front elevation view of the design of FIG. 1; FIG. 3 is a rear elevation view of the design of FIG. 1; FIG. 4 is a right side elevation view of the design of FIG. 1; FIG. 5 is a left side elevation view of the design of FIG. 1; FIG. 6 is a top plan view of the design of FIG. 1; and, FIG. 7 is a bottom plan view of the design of FIG. 1.

The dash-dash broken lines in the figures depict portions of the storage device that form no part of the claimed design.

1 Claim, 7 Drawing Sheets---
